UNITED STATES PATENT OFFICE.

FRANK LA OTIS LATHROP, OF WALLINGFORD, CONNECTICUT, ASSIGNOR TO H. L. JUDD COMPANY, OF WALLINGFORD, CONNECTICUT, A CORPORATION OF NEW YORK.

CURTAIN-ROD.

1,055,925.

Specification of Letters Patent. Patented Mar. 11, 1913.

Application filed August 17, 1912. Serial No 715,531.

To all whom it may concern:

Be it known that I, FRANK LA OTIS LATHROP, a citizen of the United States, residing at Wallingford, county of New Haven, State of Connecticut, have invented certain new and useful Improvements in Curtain-Rods, of which the following is a full, clear, and exact description.

My invention relates to improvements in curtain rods of the type designed to support sash curtains, and the main object of the invention is to provide in an extension curtain rod of this type, means for holding it against accidental displacement.

15 In the drawings, Figure 1 is a front elevation of a curtain rod with its brackets, a portion of the rod being broken away; Fig. 2 is a plan view of the same; Fig. 3 is a relatively enlarged detail view partly in section; Fig. 4 is a cross-section on the line $x-x$, Fig. 3; Fig. 5 is a view similar to Fig. 3, showing a slight modification; and, Fig. 6 is a section on the line $y-y$, Fig. 5. Fig. 7 is a fragmentary top plan view, with parts 25 broken away, illustrating the engagement of the rod ends with the brackets.

1-2 represent two telescopic sections of a tubular curtain rod.

3-4 represent brackets of any suitable design arranged to support the aforesaid rod sections.

3^a represents the end of the bracket 3, which is designed specially to receive the end of the curtain rod in such a manner as 35 to hold it against accidental displacement.

This bracket end 3^a and the end of the adjacent section of the curtain rod are specially formed in such a manner that these parts are connected by a spring lock. While, in fact, both ends of the curtain rod are similarly constructed to form sockets to engage corresponding brackets at each end, a description of one of said connections will be sufficient. The rod end 3^a is provided 45 with an annular groove 5. The rod section 1 is provided with an inwardly directed annular rib 6, designed to fit into the annular groove 5. The rod section, at its end at least, is split longitudinally, either specially or 50 incidental to the manufacture of the tube. Since the rod section is split, it follows that it may be sprung open somewhat upon pressure being applied. The extremity of the bracket end 3^a is preferably rounded or 55 tapered so as to easily enter the end of the

tube and force its way through the contraction formed by the annular rib 6. In the preferable construction, the socket end of the rod section is covered by a ferrule or tubular cap 7, which is secured to the rod in 60 such a manner as to reinforce the same, while at the same time permitting that part of the rod containing the rib 6 to spring open somewhat to permit the bracket end 3^a being inserted fully into place, as shown 65 in Fig. 3. The method of connecting the tubular cap or reinforcement 7 may comprise an overhanging flange 8 at one end and a contracted portion 9 at the other end pressed into a groove or around a shoulder 70 formed on the rod section 1.

In the modification shown in Fig. 5, the construction is similar to that previously described, with the single exception that a C-shaped spring 10 is located in the groove 75 back of the rod 6, said C-shaped spring exerting a pressure in a direction to force the said rib into the annular groove 5, thus giving added security and furnishing a construction which is preferable when the metal 80 of the tube 1 is of comparatively small gage.

What I claim is:

1. In a curtain rod, a sliding tubular rod section having a socket end, said socket end being split longitudinally, a bracket support arranged to enter said socket end, an annular groove on one part and a projection on the other part arranged to enter said groove and hold said parts against accidental displacement, and a stationary sleeve carried 90 by said rod section spaced from and inclosing the split socket end thereof.

2. In a curtain rod, a sliding tubular rod section having a socket end, said socket end being split longitudinally, a bracket support 95 arranged to enter said socket end, an annular groove on said bracket support, and a transversely arranged rib on the inner side of said split socket end arranged to enter said groove, and a stationary sleeve carried 100 by said rod section spaced from and inclosing the split socket end thereof.

3. In a curtain rod, a sliding tubular rod section having a socket end, said socket end being split longitudinally and having a stationary sleeve spaced from and inclosing its split portion, a bracket support arranged to enter said socket end, an annular groove on said bracket support, a transversely arranged rib on the inner side of said split 110

socket end arranged to enter said groove, and a spring embracing said split socket end.

4. In a curtain rod, a sliding tubular rod section having a socket end, said socket end being split longitudinally, a bracket support arranged to enter said socket end, an annular groove on said bracket support, an indented transversely extending rib on the inner side of said split socket end arranged

to enter said groove, a spring ring embracing said split socket end and seated in said rib indentation, and a stationary ferrule carried by said rod section and spaced from and inclosing the split socket end thereof.

FRANK LA OTIS LATHROP.
